UNITED STATES PATENT OFFICE.

CASPER SCHULTZE AND J. F. SCHRODER, OF COVINGTON, KENTUCKY.

STRAW-CUTTER.

Specification of Letters Patent No. 25,530, dated September 20, 1859.

To all whom it may concern:

Be it known that we, CASPER SCHULTZE and J. FREDERICK SCHRODER, of the city of Covington, county of Kenton, and State of Kentucky, have invented a new and improved machine for cutting vegetables for culinary purposes, such as cabbage, apples, potatoes, turnips, &c., also for cutting straw for chop feed, &c.; and we do hereby declare 10 the following to be an exact and full description of the same, viz:

The nature of our invention consists in providing a revolving wheel with a series of adjustable knives, one end of the knives 15 pointing to the axle upon which the wheel revolves, and the other end of said knives radiating to the periphery of the wheel to which they are fastened. The wheel—its face which carries the knives—revolves close 20 to a chute through which the articles are fed to the machine, when it is in operation; and, not only are the knives made adjustable,—so that they can be made to cut coarse or fine—but, the chute is made adjustable 25 also—by which means it can be moved as close to, or, as far from the knives as may be desired.

To enable others, skilled in making machines of this class, to make and use our adjustable universal cutter, we will now proceed to describe the same, and, in doing this, reference is directed to the accompanying drawings, and the letters of reference marked thereon—like letters referring to 35 like parts—and we desire that they shall also constitute a part of our description.

Figure 1—is an elevated, perspective view of the machine. Fig. 2—is the face of the knife wheel—showing the relation of the 40 knives to each other, where four knives are used. Fig. 3—is a view of the knife wheel and the feeding chute—showing their relation to each other. Fig. 4—is the same as Fig. 3—with the difference that in Fig. 4 45 the edge of the knife wheel is shown as also—the shaft upon which the wheel is

keyed fast—and the crank by means of which it is revolved—in its use.

A, A, is a substantial frame—made in the style of an oblong box. It may be made 50 three feet high, as many in length, and, from six to twelve inches in thickness.

B, B, are legs to support the box off of the ground, or floor.

c, c, are brackets, or cleats firmly attached 55 to the side of the box—one on each side of the hole through which the chute C, C, passes.

e, e, slots, into which the thumb screws G, G, are made fast, and which allows of 60 the variable movement of the chute C.

D, D, D, D, are steel knives, from one foot to 18 inches long; fastened into one face of wheel H.

Wheel H, is from two to three feet in 65 diameter,—and is constructed of an arm for each of the four knives, and these are stationary upon the shaft if desired while those portions of the wheel between the knives are so arranged as to slip upon the shaft— 70 thus enabling the operator to enlarge or contract the knife throat at pleasure.

Having thus described our invention, we wish to disclaim the construction of a cutting box with a rotating knife wheel as 75 original with us, as we are aware that such are old, but;

What we do claim as original and desire to secure by Letters Patent, is—

A cutting box constructed as before shown 80 and specified,—that is—with adjustable compound knife wheel H, in combination with feeding chute C,—when these several parts are constructed and arranged for operation conjointly as, and for the purposes described.

CASPER SCHULTZE.

J. FREDERICK SCHRODER.
